UNITED STATES PATENT OFFICE.

WILLIAM V. D. KELLEY, OF BROOKLYN, NEW YORK.

SOCKET AND ATTACHMENT PLUG.

1,320,150.

Specification of Letters Patent. Patented Oct. 28, 1919.

Application filed July 20, 1916. Serial No. 110,284.

To all whom it may concern:

Be it known that I, WILLIAM V. D. KELLEY, a citizen of the United States, residing at Brooklyn, in the county of Kings and State 5 of New York, have invented certain new and useful Improvements in Socket and Attachment Plugs, of which the following is a full, clear, and exact specification.

This invention relates to socket and attachment plugs, and has particular reference to the provision of both a socket and an attachment plug, which can be inserted at one end into an ordinary socket, and having means at the other end for connection to a lamp or 15 lamp cord.

The object of the invention is to combine in both an attachment and a socket plug, such as an automatic thermostatically actuated controlling switch for a translating device or for flashing a lamp. The invention is of general application, although it is intended more especially for the flashing of lamps which are used in connection with advertising devices, etc.

By this invention, there is provided within a cylindrical casing of about the ordinary diameter of a standard lamp socket, a complete flashing switch, which only has to be screwed into the socket at one end and connected to a lamp at the other end to form a 25 flashing unit. A particular feature of the invention resides in a novel conducting shell, and the invention further comprises the construction and arrangement of parts whereby 30 the switch can be adjusted while connected in the light circuit, without either taking the flasher apart, or liability of producing a short circuit. While flashing devices adapted for connection at one end with a lamp 35 are known, none of them which have gone into practical use, so far as I am aware, have been capable of adjustment while in operation, but have had to be disconnected and 40 taken apart for adjustment and then reassembled for trial. In such an arrangement there is no way of telling whether the adjustment is right or not, but by means of this invention, the adjustment can be made 45 while the switch is connected in the circuit and any defect easily corrected.

The invention comprises both a socket plug, which receives the controlled device directly, such as a lamp, and an attachment 55 plug, which is to be connected with the trans-

lating device at a distance by means of a cord.

In the accompanying drawing,—

Figure 1 is a cross-section showing a 60 socket plug embodying the invention;

Fig. 2 shows the porcelain contact and switch carrying member in side view;

Fig. 3 is a view of Fig. 2 seen from the right;

Fig. 4 is a cross-section on the line 4—4 85 of Fig. 2;

Fig. 5 is a cross-section of the shell;

Fig. 6 shows a cross-section of an attachment plug;

Fig. 7 shows an end view with the cap removed, and

Fig. 8 shows an elevation partly in section.

1 represents a socket or outlet having an internally threaded conducting shell 2 connected to one side of the circuit and a center 75 contact 3 connected to the other side of the circuit, and of any ordinary or standard construction. 4 represents the switch and contact support of insulating material, such as porcelain, upon which are mounted the 80 thermostatic switch and connected contacts from end to end forming one side of the circuit. The support 4 is attached to the shell 5 by screw 15 engaging a nut in slot 35 of support 4. The other side of the circuit is 85 formed by the inclosing shell 5 of conducting material, and outside of that is the external non-conducting insulating shell 6. The elongated support 4 is provided with a reduced end 7 which projects through the 90 open end of the shell 5 and is held by the in-turned flange 8. The end 7 carries a contact washer 9 which contacts with the center contact 3 of the socket 1 when the externally threaded end 11 of the shell 5 is screwed 95 into the conducting shell 2 of the socket. The center contact 9 is connected by a screw 12 to the switch member 13, being threaded thereto. The switch member 13 is bent as shown so as to pass into the transverse slot 100 14 in the support 4, and is threaded to receive the screw 12 to produce good electrical contact. 16 is a cooperating switch member which is secured to the opposite end of switch member 13 at 17, and the members 105 13 and 16 are also firmly fastened together on the support by screws 18 and nut 19. The switch members 13 and 16 straddle the tapered stiffening rib 20 on the support 4, as shown in Fig. 3, and are spaced from the 110

bottom of the chamber 21 formed in the other end of the support 4. The two members 13 and 16 constitute a thermostatic switch, operating to swing laterally when 5 one leg, as for example 16, is heated or cooled. The heating or cooling is effected by a heating coil 23 which is connected at one end to contact 12, as at screw 18, and at the other end is connected across the contact bar 24 which is fastened to the support 4 by screw 25. The contact bar 24 also carries an adjusting contact screw 26 which is opposite the hole 27 in the outer non-conducting shell 6 and also the larger hole 28 10 in the conducting shell 5. The shell 6 thus prevents electrical contact of the adjusting tool and shell 5. The screw 26 is adjusted toward and from the vibrating contact 29 on the connected ends of the switch members 13 and 16 to vary the period of flashing. As 15 shown herein, the heating coil 23 is in series with the circuit, or across the line, when the contact 29 is separated from contact 26. This causes heater 23 to heat the leg 16 20 causing it to be elongated and close the circuit at contacts 29 and 26. This shunts the heating coil 23 out of the circuit, allowing the heated leg to cool and open the circuit, and thereupon the operation is repeated as 25 often as the thermostat heats and cools, depending upon the adjustment of screw 26.

It is of importance to be able to adjust the contact screw 26 from the outside while the device is in circuit, which has not been 30 heretofore accomplished in devices of this character. From the contact plate 24, the current passes by screw 30 to a center contact 31 mounted on the forward end of the support 4 and capable of contacting with 35 the center contact 32 of a lamp bulb 33 screwed into the internal threads 34 on the outer end of shell 5.

The shell shown in Fig. 5, consists of the 40 socket end having the threads and the in-turned end, the intermediate cylindrical portion having the adjusting hole 28, and the outer threaded end for receiving the lamp, or a screw plug.

The combined socket plug and flasher has 45 several advantages, among which are compactness, ease of use, and absence of loose parts.

In Figs. 6, 7, 8, is shown an attachment plug for an extension cord. The attachment end is the same, but instead of the 50 socket 34, means is provided for attaching a cord 38, consisting of a block 39 interlocking by angular projection 36 with a similar recess in the end of body 37, and fastened to 55 a bar 24 by screw 40 in recess 41. The body 37 and block 39 can be integral if desired. Also fastened by screw 40 is a wire terminal plate 42 in recess 41 and set screw 43, while in recess 44 is the other wire terminal plate 60 45 and set screw 46. 47 is a contact strip

which passes through the block 39 and contacts with shell 5 inside shell 6, as shown in Fig. 7. 49 is the lamp to be flashed through the cord 38, which passes through a shell 50 and insulating bushing 51, fastened by bayonet slots and screws 52 to nuts 53 in block 39. 54 is an insulating disk within the shell 50. The operation of this form will be similar to that heretofore described, and both forms can be adjusted while in operation 70 without liability of short circuiting. The advantages of this form is that an attachment plug and flasher are combined in a unitary article which is already assembled ready for the cord without loose or separable parts which are easily lost or displaced when wanted for use. Various changes and modifications can be made in the details shown herein without departing from the 75 scope of the appended claims. 80

Having thus described my invention, I declare that what I claim as new and desire to secure by Letters Patent, is:—

1. A flashing socket plug comprising a tubular conducting shell having one end formed for insertion into an outlet socket to electrically connect said shell and the socket on one side of the circuit, an insulating support within the shell carrying a center contact to coöperate with a center contact in 90 the socket for the other side of the circuit, a thermostat mounted at one end on said support and extending longitudinally within said shell with its other end free to vibrate with changes in temperature, said thermostat being electrically connected to said shell center contact, a heating coil controlled by the movement of the thermostat for intermittently heating the thermostat, a screw contact carried by said insulating support and 95 coöperating with said thermostat, said contact being disposed transversely of said shell and the shell having an adjusting tool insertion aperture through its side adjacent the head of the screw, and a connection for a 100 lamp to be flashed connected to said screw, said shell constituting the other circuit connection of the lamp to be flashed. 110

2. A flashing socket plug comprising a tubular conducting shell having one end formed for insertion into an outlet socket to 115 electrically connect said shell and the socket on one side of the circuit, an insulating support within the shell carrying a center contact to coöperate with a center contact in the 120 socket for the other side of the circuit, a thermostat mounted at one end on said support and extending longitudinally within said shell with its other end free to vibrate with changes in temperature, said thermostat being electrically connected to said shell center contact, a heating coil controlled by the movement of the thermostat for intermittently heating the thermostat, a screw contact carried by said insulating support 125 and 130

port and coöperating with said thermostat, said contact being disposed transversely of said shell and the shell having an adjusting tool insertion aperture through its side adjacent the head of the screw, an insulating shell inclosing said conducting shell and having a registering tool insertion aperture smaller than the conducting shell aperture, and a connection for a lamp to be flashed connected to said screw, said shell constituting the other circuit connection of the lamp to be flashed.

3. A flashing socket plug comprising a tubular conducting shell having its inner end formed for insertion into an outlet socket to electrically connect said shell and the socket on one side of the circuit, and its outer end formed to receive a lamp base in electrical connection therewith, an insulating support within the shell carrying a center contact to coöperate with a center contact in the socket for the other side of the circuit, a thermostat mounted at one end on said support and extending longitudi-

nally within said shell with its other end free to vibrate with changes in temperature, said thermostat being electrically connected to said shell center contact, a heating coil controlled by the movement of the thermostat for intermittently heating the thermostat, a screw contact carried by said insulating support and coöperating with said thermostat, said contact being disposed transversely of said shell and the shell having an adjusting tool insertion aperture through its side adjacent the head of the screw, an insulating shell inclosing said conducting shell and having a registering tool insertion aperture smaller than the conducting shell aperture, and a connection from said screw carried by said insulating support adapted to connect with the center contact of a lamp when inserted into the outer end.

In testimony whereof I affix my signature, in presence of two witnesses.

WILLIAM V. D. KELLEY.
